United States Patent Office

Des. 229,120
Patented Nov. 6, 1973

229,120

COMBINED LIPSTICK AND LIP GLOSS POT

Jess A. Bell, Rocky River, Ohio, assignor to Eyelet
Specialty Company, Wallingford, Conn.

Filed May 18, 1972, Ser. No. 254,827

Term of patent 14 years

Int. Cl. D28—02

U.S. Cl. D86—10 G

FIG. 1 is a perspective view of an embodiment of my design;

FIG. 2 is a view in elevation;

FIG. 3 is a top view; and

FIG. 4 is a bottom view.

I claim:

The ornamental design for a combined lipstick and lip gloss pot, substantially as shown.
